UNITED STATES PATENT OFFICE.

CHARLES E. REED, OF CHICAGO, ILLINOIS.

WOODWORKING-MACHINE.

1,246,465.

Specification of Letters Patent. Patented Nov. 13, 1917.

Application filed July 26, 1917. Serial No. 182,885.

To all whom it may concern:

Be it known that I, CHARLES E. REED, a citizen of the United States, residing at Chicago, in the county of Cook and State 5 of Illinois, have invented a new and useful Improvement in Woodworking-Machines, of which the following is a specification.

My invention relates to improvements in wood-working machines of the type where- 10 in a pattern-tracer element and a wood-cutting element or elements are provided, together with means whereby the movement of the pattern-tracer around a pattern is translated into movement of the wood-cutting element or elements as the case may be, to cause the work to be turned to the same shape as that presented by the pattern, machines of this type being so constructed that during the progress of the wood turning op- 15 eration, the mechanism which supports the pattern and work, and the pattern-tracer and wood-cutting element or elements as the case may be, are moved relative to each other to effect the feeding, so-to-speak, of 20 the work to the tracer and cutting elements, my invention relating more particularly to machines of the above referred to type wherein the cutter element or elements, are caused to move around and in contact with 25 the side of the work to be operated on, in paths corresponding with the paths through 30 which the pattern-tracer moves in traveling around the pattern, by means of mechanism which includes a rotatable member prefer- 35 ably in the form of a gear, and a gyratory member supported at one end to move in a gyratory path and operatively engaging the 40 said rotatable member eccentrically of the axis of rotation of said rotatable member, when the pattern-tracer and cutters are 45 shifted to a position in which they extend to one side of their normal position, such position being presented when the pattern-tracer engages the side of a pattern, and means 50 tending to cause said gyratory member to occupy a central position in which it coincides with the axis of said rotatable member, and which in the operation of the machine causes the pattern-tracer to closely hug 55 the surfaces of the pattern in its movement around the latter, the engagement of the gyratory member with the rotatable member as stated, being in the nature of a crank connection, a machine of the particular type just described being illustrated and de-

scribed in U. S. Letters Patent 1,196,716 granted August 29th, 1916, and for use in connection with which I have more particularly devised my improvements, though the latter may be used in connection with ma- 60 chines the construction of which varies from that disclosed in said patent.

The speed of movement of the pattern-tracer and cutters in their movement about the pattern and work respectively, is de- 65 pending firstly upon the speed at which the above referred to rotatable member with which the gyratory member has crank en- gagement, rotates, and secondly upon the 70 distance from the center of said rotatable member to the axis of the gyratory member where it operatively engages said rotatable member, it being manifest that, assuming the rotatable member to be driven at a con- 75 stant speed, the farther from the center of the rotatable member the gyratory member 80 engages it, the faster the pattern-tracer and cutters will move. Thus when the pattern-tracer is traveling around a pattern having sloping sides as in the case of a shoe last, it 85 will travel much faster about the portion of the last which is relatively large, than when it is traveling around the portion of the last which is relatively small. Furthermore this same feature of varying speeds of travel of 90 the pattern-tracer and cutters is presented in the use of a machine of this type for operating on work which is to be fashioned in conformance with a pattern which is either of angular shape in cross-section or of 95 relatively great width in one direction com- 100 pared with the direction at right angles thereto, as in the case of the toe-portion of a last, and in fact in connection with any kind of a pattern which is not truly circular in cross-section and the exterior surfaces of 105 which to be operated on are not concentric relative to the cutters. For purposes of illustration and to show how this feature works out in practice, the case of the toe-portion of the last will be considered. As 110 the tracer in moving around the toe-portion of the last, moves outwardly against one of the flattened surfaces of the last, away from the axis of the last, the gyratory member shifts at its point of operative engagement with the said rotatable member toward the circumference of the latter and as the speed of rotation of the said rotatable member is substantially constant the movement of the 115

pattern-tracer and cutters will be accelerated in the proportion that the gyratory member has moved away from the center of the rotatable member. Thus the speed of movement 5 of the pattern-tracer and cutters instead of being a substantially uniform movement in traveling about a surface such as that described, is so non-uniform and varying that if the machine is geared up to such a point 10 that it will operate relatively rapidly to perform its work, the tracer and cutters will have a jerky movement as they travel around the pattern and work respectively, producing chattering and jumping of the cutters 15 with the result that the work produced by the machine is not up to the desired standard, if the machine is to be operated at a reasonable speed. Furthermore in the operation 20 on work of tapered formation, the setting of the machine to cause the pattern-tracer and cutters to move at a certain speed when traveling about the larger portion of the work, while causing the pattern-tracer and cutters to make the same number of 25 revolutions about the work when engaging the smaller portion thereof as they do when engaging the larger portions thereof, will cause the pattern-tracer and cutters to move very much slower than when engaging the 30 larger portions of the work and it is manifest that this is undesirable in a machine provided for operation under general commercial conditions, as the time required for finishing the work is unduly long, and under 35 ordinary conditions the operation of the cutters on the smaller portions of the work at a speed faster than the speed at which they operate on the larger portions of the work, is more conducive to the practical operation 40 of the machine.

The machines of the construction shown in said patent have been provided with manually operated speed changing mechanism whereby the operator of the machine could 45 control the speed at which the rotatable member travels. Such controlling mechanism however, while serving as a means for controlling the speed of the rotatable member to accelerate it as the cutters approached 50 the extremity of the work, as for example the last, at the smaller end thereof, do not present any means whereby the operator, even if he remained stationed at the machine, could practically control the speed at 55 which the pattern-tracer and cutters moved around the work where it is irregular as above stated, and render the speed of movement of the tracer and cutters uniform, or substantially uniform, to avoid the chattering 60 and jumping referred to.

My primary object is to provide in a machine of the character above stated, means which shall operate automatically to control the speed of the said rotatable member, or 65 its equivalent element, to the end of render-

ing uniform or substantially uniform the speed at which the pattern-tracer and cutters move in making any given revolution about the pattern and work, respectively, thereby avoiding the chattering and jumping of the tracer and cutters, producing a high grade of work, in as much as the work turned out by the machine is an exact reproduction in shape of the pattern, permitting the machine to be operated at the maximum speed and producing maximum efficiency and economy of operation. A further object is to provide for the automatic speeding up of the machine in the movement of tracer and cutters from portions of the 70 work, to portions thereof of less cross-sectional area, as in the case of tapered work, which feature also permits the machine to operate with the greatest efficiency and economy, and with maximum capacity. 75 Another object is to provide means of the character just discussed which shall be adjustable to vary the proportions between the speed at which the pattern-tracer and cutters revolve about the tracer and work 80 when traveling throughout a path of a given length, and the speed at which these elements travel when moving through a path of less length, to adapt the machine to perform the most effective work in operating 85 upon different sizes and shapes of work, and another object is to provide an arrangement of spring-devices whereby danger of indenting the pattern, or rounding sharp corners thereof will be avoided. 90

Inasmuch as I have devised my improvements for use more particularly in connection with the general construction of the machine illustrated and described in the above referred to patent, I have chosen to 95 illustrate it in connection therewith, where- in in the drawings:

Fig. 10—A view taken along the line 10 in Fig. 8 and viewed in the direction of the arrow.

10 Inasmuch as the general features of the machine illustrated are the same as those of the machine illustrated and described in the said patent, a general description thereof only will suffice, this description being as 15 follows:

The upright frame portion of the machine is represented at 20, this frame carrying the operative parts of the machine. At one side of this frame and confined thereon, to be 20 vertically movable, is a carriage 21, which in the operation of the machine is caused to slowly descend during the operation of the pattern-tracer and cutter elements as hereinafter described. This carriage is 25 equipped at its upper end with outwardly extending spaced arms 22 in the outer ends of which a yoke-shaped work-holder member 23 is trunnioned to adapt it to be rotated upon the arms 22 through an arc of substantially 180°, the means for swinging the work-holder over from one position to the other thereof and holding it rigidly in the position to which it is moved being represented at 24. The work-holder 23 is 30 provided with clamping devices for receiving and holding in spaced relation a plurality of pieces of work to be operated upon, as for example the lasts represented at 25, and the pattern, it being understood that these lasts 35 and pattern which extend in a general vertical direction, are disposed in a substantially horizontal series across the front of the machine and that either ends of the lasts 25 may be operated on to trim off the stubs 40 thereon, by adjusting the work-holder about its trunnions.

The pattern-tracer is represented in Fig. 3 at 26 and the upper ends of the cutter devices at 27, these devices being mounted on a 45 plate 28, the cutters 27 to be rotatable thereon and the latter continuously rapidly rotated by means of belts 29 driven from a roller 30 in turn driven by a belt 31 from a pulley 32 this pulley being carried by a shaft 33 driven by any suitable means. The slide 28 is mounted to be freely movable across the front of the machine in a horizontal direction, this slide being so mounted upon a member 38, which is guidedly confined on 50 the upper portion of the frame 20 to have straight-line movement in a horizontal plane from front to rear of the machine. The member 38 carries a horizontal extending lever 39 pivotally supported, intermediate 55 its ends, as represented at 40, this lever be-

ing pivotally connected at its forward end as indicated at 41, with a link 42 which in turn is pivotally connected at 43 with the slide 28. The rear end of the lever 39 is pivotally connected at 44 with a link 45 70 which is pivotally connected with a post 46 which extends downwardly through a slide 47 mounted on an underlying slide 48, to be movable crosswise of the latter, or in other words at substantially a right angle to the 75 line of movement of the slide 38, the slide 48 being guidedly confined at bearings 49 on the upper portion of the casing 20, to be movable horizontally substantially in the same direction as the line of movement of the 80 slide 38. The post 46 extends downwardly at a collar portion 50 thereon into and through a radially-disposed slot 51 in a gear 52 rotatably mounted in the upper portion 85 of the casing 20, this gear being driven by mechanism hereinafter described.

The post 46 has a journal fit in the upper open end of a tubular member 53 having a foot portion 54 in the form of a ring which bears flatwise against the bottom of a groove 90 55 in a seat 56 supported on a cross member 57 provided in the casing 20, the member 53 bearing flatwise at its portion 54 against the seat referred to, or in other words extending at substantially a rightangle to the plane of 95 said seat when the post 46 extends coincident with the axis about which the gear 52 rotates. When the pattern-tracer and cutters are moved out of centralized position, as is the case where the pattern-tracer engages a side of the pattern as illustrated of the cutter relative to the last 25 in Fig. 1, the slides connecting the pattern-tracer and cutters with the post 46 are moved out of 100 normal position and the post 46 extends in 105 the slot 51 eccentrically of the center of the gear 52 as represented in Fig. 4, in which position the member 53 is tilted out of vertical position as shown in Fig. 4. As the gear 52 continues to rotate so long as the pattern-tracer engages the side of the pattern, the member 53 will move in a gyratory path around its normal central plane by reason of the crank action of the gear on this member. A spring 58 located in the member 53 110 connects at its upper end with the cross-pin 59 in the member 53 and at its lower end with a flexible member, such as the chain 60 illustrated which extends downwardly through the seat 56, over a pulley 61 and 115 connects with an adjustable device 62 for varying the tension of the spring. This spring, together with another spring herein-after described in the particular illustrated construction, operates to yieldingly maintain 120 the member 53 in upright centralized position and by constantly pulling on the member 53 tending to right it, causes the pattern-tracer to hug the pattern as it revolves 125 around the latter, the cutters by revolving 130

in paths corresponding with the paths through which the tracer moves, cutting the work to a form corresponding with that of the pattern.

5 The gear 52 meshes with a pinion 61 mounted on the upper end of a shaft 62 journaled in a bearing 63 in the casing 20, the lower end of this shaft being equipped with a miter-gear 64 which meshes with a 10 similar gear 65 on a shaft 65^a journaled in the machine and carrying at its outer end a disk 66 which coöperates with a friction-roller 67 mounted on a shaft 68 supported in bearings 69 and 70 provided at the upper 15 ends of arms 71 and 72 rising from a sleeve 73 journaled on a shaft 74 fixed in a housing 75 extending rearwardly from the casing 20, the outer end of the shaft 68 carrying a pulley 76 belted as by the belt 77, to a pulley 20 78 on a shaft 35, driven by a belt 36 which connects a pulley 37 on the drive-shaft 33 with a pulley 34 on the shaft 35. The roller 67 is rigid with a sleeve 200 which is supported from the shaft 68 by ball bearings 25 201 arranged about this shaft, preferably with the balls staggered, certain of these balls, represented at 202, being larger than the others and arranged in a series extending lengthwise of the shaft 68 and located in 30 grooves 203, 204 respectively, in this shaft and sleeve. The balls are retained in a ball-retainer of sleeve form and operate to permit the sleeve 200 and roller 67 to slide along the shaft 68 but be held against independent 35 rotation thereon. It will be understood from the foregoing that by sliding the friction roller 67 across the face of the disk 66 toward the center of the latter, the speed at which this disk is rotated is materially increased and when this roller is moved 40 across the face of the disk away from its center the speed of the disk is correspondingly decreased. Furthermore the provision of the rocking bearing-frame permits of the 45 movement of the friction roller 67 into and out of a position in which it frictionally bears against the face of the disk 66 thereby affording a means for controlling the connection of the disk 66 and the parts operated thereby, with the driving power of the 50 machine. In the particular construction of machine illustrated the swinging of the pivotally mounted member in which the shaft 68 is journaled is effected through the medium of a rod 68^b having a spring connection of the same general character as that shown in the said patent, with a post 68^b rising from the bearing 69 of the rocking-frame, this rod having pivotal connection at 55 79 with a crank 80 on a rotatable member 81 journaled in a plurality of bearings on the outer side of the casing 20, this member 81 also having a crank section 82 which connects by a rod 83 with a crank arm 84 pivotally supported and controlled by a lever 85

as in the said patented construction, the mechanism just referred to operating when the lever 85 is moved in one direction to swing the frame carrying the shaft 68 to a position in which the roller 67 is out of engagement with the disk 66 and when moved in the opposite direction to swing this frame to a position for causing the roller 67 to frictionally engage the disk 66. The mechanism for automatically stopping the rotation 70 of the gear 52 when the cutters have completed the operation of cutting the work involves the rod 68^a, crank 80, crank 87 and a pawl-lever 88 operating as in the case of the said patented construction. 75

According to my invention means are provided, as above stated, for automatically controlling the speed of rotation of the gear 52 to render uniform throughout any given path of movement, the speed at which the 80 pattern-tracer and cutters revolve about the pattern and the work respectively, and also to speed up the movement of the tracer and cutters about the pattern and work, respectively, as the tracer and cutters move from the relatively large portions of the pattern and work to the relatively small portions thereof, as presented by work of tapering form. 85

The following is a description of this 90 mechanism when constructed in accordance with the preferred embodiment of my invention. Journaled to extend transversely through the casing 20, is a shaft 90, the end thereof which extends through the rear wall 100 of the said casing carrying a crank 91 clamped to the shaft 90 by means of a clamping screw 92 engaging the split portions 93 of the portion of the said crank which surrounds the shaft. Rising from the outer 105 end of the crank 91 and secured thereto in a slot, as by a set-screw 94, is a spring-bar 95, preferably of laminated construction, which extends into a slot in a head 96 in which it is secured by a set-screw 97. A link 98, pivotally connected with the head 96 as by the pin 99, extends laterally of the bar 95 and is pivotally connected with a screw device 100 forming a part of a clamping device 101 which is adjustable up and down in a slot 110 102 in the lower end of a lever 103 journaled at its upper end on a shaft 104 extending rearwardly from the casing 20. The clamping device referred to in the particular construction shown is formed of the screw 100 which has threaded thereon a sleeve-section 105 extending part-way through the slot 102 and provided with an angular head 106, and a wing-nut 107 screwing upon the end of the screw device 100. 115 The lever 103 is embraced between the head 106 and wing-nut 107, which operate to clamp this lever between the head 106 and wing-nut 107 and hold the clamping device 120 in adjusted position along the slot 102, while 125 130

maintaining the pivoted connection of the link 98 with the screw 100, as illustrated in Fig. 10. The lever 103 contains in the slot 102, below the adjustable clamping device 101, a similar clamping device 108 forming a pivotal connection for a link 109, this link also having pivotal connection with an adjustable clamping device 110 like the clamping device 101, adjustable up and down in a slot 111, in a lever 112 journaled at its lower end on a pin 113 extending rearwardly from the casing 20, the upper end of the lever 112 being provided with a pin 115 forming journal support for a roller 114 which extends into an annular groove 116 in the periphery of the sleeve 200, whereby when the lever 112 is rocked on its fulcrum 113 it will shift the sleeve 200 and consequently the roller 67 along the shaft 68 toward or away from the center 20 of the disk 66 depending on the direction in which the lever is rocked, and thereby control the speed at which the disk 66 is rotated.

The spring hereinbefore referred to as co-operating with the spring 58 is represented at 112^a, this spring being connected at one end to the lever 112 and at its opposite end to a post 20^a on the standard 20 by an adjustable connection 112^b. The spring 112^a is preferably so adjusted that when the parts 30 occupy the positions shown in Fig. 8 this spring will be under practically no tension.

In accordance with my invention the shaft 90 is rocked in one direction or the other responsive to the change in the angle at 35 which the member 53 extends relative to the plane occupied by it when in centralized position, the greater the angle at which this member tilts the greater the rocking movement of the shaft 90 in a direction for shifting the friction roller 67 away from the center of the disk 66 to slow down the speed of rotation of the gear 52, the preferred mechanism for effecting the rocking of the shaft 90 being that shown and of which the following is a description. Surrounding the lower end of the tube 53 is a universal joint 117 formed of a hollow frame-like member 118 into two opposite sides of which threaded pins 119, screw. The inner ends of 50 these pins are unthreaded and extend inwardly beyond the member 118 and have journal fit in diametrically-opposed openings 120 in the lower end of the tube 53 whereby the frame member 118 is free to have rocking movement on the tube 53. The lower end of the tube 53 at the diametrically-opposed portions thereof at substantially a right angle to the line connecting the pivots 120 is cut away as represented in Fig. 6, and the member 118 adjacent these cut-away portions and midway between the ends of the member 118 is provided at its opposite sides with headed pins 121 to the outer ends of which depending parallel bars 122 are pivotally connected, these bars having connection at

their lower ends with the ends 123 of a block 124 which is pivotally connected with the arms 125 provided on the upper side of a crank 126, pinned as indicated at 127, to the shaft 90 by means of pivot pins 128, the connection thus afforded between the bars 122 and the crank 126 being in the nature of a universal joint. By the connections thus provided between the crank 126 and the tube 53 the latter is free to gyrate as hereinbefore described and rock the shaft 90 through the medium of the crank 126, responsive to the movement of the member 53 toward and away from the plane it occupies when in centralized position.

It will be clearly understood from the foregoing that, assuming the pattern-tracer to be co-operating with a pattern of angular shape in cross-section or of relatively greater width in one direction than in a direction at right angles thereto, as the tracer in moving against the side of the pattern, is forced away from centralized position, or in other words, as it starts to go around the corner of the pattern, the post 46 co-operating with the gear 52, will move outwardly in the slot 51, thus tilting the member 53 to a greater degree with the result of lifting the hereinbefore described mechanism connected with the lower end of the member 53 and rocking the shaft 90 in counter-clockwise direction in Figs. 2 and 5, with the result of shifting the roller 67 on the shaft 68 away from the center of the disk 66 through the medium of the bar 95, link 98, lever 103, link 109 and lever 112, which slows down the speed at which the gear 52 rotates, and the reverse action takes place when the pattern-tracer in moving around the pattern, moves in a direction toward the plane in which the pattern-tracer normally extends when it is out of engagement with a pattern.

It will be noted that the rotary movement of the shaft 90 is communicated to the roller 67 for sliding it along the shaft 68 by means of the above referred to bar, links and levers which by being adjustably connected with each other as hereinbefore explained, adapts the machine to be so set that the speed at which the pattern-tracer moves around a pattern may be rendered uniform or substantially so, and the speed at which the pattern-tracer is caused to travel may be regulated as desired. Furthermore by the adjustable features just referred to, the speed at which the pattern-tracer travels around the small end of a pattern relative to the speed at which it travels around the larger portion thereof may be varied as desired, to render the speed of rotation of the tracer throughout the operation of cutting an end of the work, uniform or substantially uniform or greater or less than during the movement of the tracer around the smaller end of the pattern. However, as under the con-

ditions presented, especially when operating on lasts, it is practicable and desirable for the most economical operation of the machine and the greatest efficiency of operation, to increase the number of revolutions made by the pattern-tracer for any given length of time when traveling around the small end of the pattern, the adjustable parts last above referred to are preferably so adjusted as to produce the result just stated, this being possible by adjusting the various links relative to the levers 103 and 112.

In the particular construction of machine illustrated the brake device for coöperation with the disk 66 for quickly stopping the latter when the roller 67 is moved out of engagement therewith in the stopping of the gear 52, comprises a brake-shoe 129 mounted on the inner end of a pin 130 projected forwardly from a depending extension 131 on the sleeve 73. By this arrangement when the frame in which the shaft 68 is journaled is rocked to move the roller 67 out of engagement with the disk 66, the brake-shoe 129 moves into engagement with this disk and arrests rotation of the latter.

The arm 95 is preferably of laminated spring construction as above stated in order that there will be a slight give to this part of the mechanism and cause it to operate more smoothly than it would if all of the connections were rigid. While the provision of the two springs is not essential to the positioning of the more essential feature of my invention, this feature is desirable, as thereby the spring tension necessary to prevent the cutting element, or elements, from jumping when the latter are moving through a relatively long path, is provided, without objectionable spring tension when the cutter, or cutters, are moving through relatively short paths.

While I have illustrated and described a particular construction embodying my invention, I do not wish to be understood as intending to limit it thereto, as the same may be variously modified and altered without departing from the spirit of my invention, it being my intention to claim my invention as fully and completely as the prior state of the art will permit.

What I claim as new and desire to secure by Letters Patent is:—

1. In a wood-working machine, the combination of a pattern-tracer, a cutter, means operatively connecting together said tracer and cutter, means for causing said tracer to move around, and in contact with, a pattern, and so constructed and arranged that under substantially uniform speed of an element thereof, the speed of movement of the tracer while in engagement with the pattern will be greater or less, respectively, as the tracer moves away from, or toward, the axis of the

pattern, and means operating automatically to cause said element to be driven slower when said tracer moves away from the axis of the pattern and to cause said element to be driven faster as said tracer moves toward the axis of the pattern. 70

2. In a wood-working machine, the combination of a pattern-tracer, a cutter, means operatively connecting together said tracer and cutter, means for causing said tracer to move around, and in contact with, a pattern, and so constructed and arranged that under substantially uniform speed of an element thereof, the speed of movement of the tracer while in engagement with the pattern will 80 be greater or less, respectively, as the tracer moves away from, or toward, the axis of the pattern, and adjustable means operating automatically to cause said element to be driven slower when said tracer moves away 85 from the axis of the pattern and to cause said element to be driven faster as said tracer moves toward the axis of the pattern.

3. In a wood-working machine, the combination of a pattern-tracer, a cutter, means operatively connecting together said tracer and cutter, means for causing said tracer to move around, and in contact with, a pattern, and including a rotatable member and a member having engagement with said rotatable member and actuated by the latter to travel about the center of said rotatable member when said tracer engages a pattern, said second-named member being shiftable toward, and away from, the center of said rotatable member, the position occupied by said second-named member relative to the center of said rotatable member being dependent on the thickness of that portion of the pattern which is in engagement with the 105 tracer, and means operating automatically to reduce the speed at which said rotatable member travels when said second-named member moves away from the center of said rotatable member and to increase the speed 110 at which said rotatable member travels when said second-named member moves toward the center of said rotatable member. 95

4. In a wood-working machine, the combination of a pattern-tracer, a cutter, means operatively connecting together said tracer and cutter, means for causing said tracer to move around, and in contact with, a pattern, and including a rotatable member and a member having engagement with said rotatable member and actuated by the latter to travel about the center of said rotatable member when said tracer engages a pattern, said second-named member being shiftable toward, and away from, the center of 120 said rotatable member, the position occupied by said second-named member relative to the center of said rotatable member being dependent on the thickness of that portion of the pattern which is in engagement with the 125 tracer, and means operating automatically to reduce the speed at which said rotatable member travels when said second-named member moves away from the center of said rotatable member and to increase the speed 130 at which said rotatable member travels when said second-named member moves toward the center of said rotatable member. 100

tracer, and adjustable means operating automatically to reduce the speed at which said rotatable member travels when said second-named member moves away from the center of said rotatable member, and to increase the speed at which said rotatable member travels when said second-named member moves toward the center of said rotatable member.

5. In a wood-working machine, the combination of a pattern-tracer, a cutter, means operatively connecting together said tracer and cutter, means for causing said tracer to move around, and in contact with, a pattern, and including a rotatable member and a member having engagement with said rotatable member and actuated by the latter to travel about the center of said rotatable member when said tracer engages a pattern, said second-named member being shiftable 10 toward, and away from, the center of said rotatable member, the position occupied by the said second-named member relative to the center of said rotatable member being dependent on the thickness of that portion 15 of the pattern which is in engagement with the tracer, and means operating automatically to reduce the speed at which said rotatable member travels when said second-named member moves away from the center of said rotatable member and to increase the speed at which said rotatable member travels when said second-named member moves toward the center of said rotatable member, said last-named means including a plurality 20 of levers adjustably connected together by links.

6. In a wood-working machine, the combination of a pattern-tracer, a cutter, means operatively connecting together said tracer and cutter, means for causing said tracer to move around, and in contact with, a pattern, and including a rotatable member, a friction disk operatively connected with said member and adapted when driven to rotate the latter, a driven roller adapted to drive said disk and shiftable relative to said disk, to vary the speed at which the latter is rotated, and a member having engagement with said rotatable member and actuated by the latter 45 to travel about the center of said rotatable member when said tracer engages a pattern, said second-named member being shiftable toward, and away from, the center of said rotatable member, the position occupied by 50 said second-named member relative to the center of said rotatable member being dependent on the thickness of that portion of the pattern which is in engagement with the tracer, and means operating automatically 55 to shift said roller relative to said disk to a position for reducing the speed at which said rotatable member travels when said second-named member moves away from the center of said rotatable member and to move 60 said roller relative to said disk to a position 65

in which the speed at which said rotatable member travels is increased when said second-named member moves toward the center of said rotatable member.

7. In a wood-working machine, the combination of a pattern-tracer, a cutter, means operatively connecting together said tracer and cutter, means for causing said tracer to move around, and in contact with, a pattern, and including a rotatable member, a member having engagement at one end with said rotatable member eccentric of the axis of the latter and actuated by the latter to travel about the center of said rotatable member when said tracer engages a pattern, said second-named member being shiftable toward, and away from, the center of said rotatable member, and means for drawing said second-named member into a position in which it is concentric with the axis of said rotatable member, the position occupied by said second-named member relative to the center of said rotatable member being dependent on the thickness of that portion of the pattern which is in engagement with the tracer, 80 and means operating automatically to reduce the speed at which said rotatable member travels when said second-named member moves away from the center of said rotatable member, and to increase the speed at 85 which said rotatable member travels when said second-named member moves toward the center of said rotatable member.

8. In a wood-working machine, the combination of a pattern-tracer, a cutter, means operatively connecting together said tracer and cutter, means for causing said tracer to move around, and in contact with, a pattern, and including a rotatable member, a member having engagement with said rotatable member and actuated by the latter to travel about the center of said rotatable member when said tracer engages a pattern, said second-named member being shiftable toward, and away from, the center of said rotatable member, the position occupied by said second-named member relative to the center of said rotatable member being dependent on the thickness of that portion of the pattern which is in engagement with the tracer, and relatively movable elements through the medium of which said rotatable member is actuated, and means operating automatically to reduce the speed at which said rotatable member travels when said second-named member moves away from the center of said rotatable member, and to increase the speed at which said rotatable member travels when said second-named member moves toward the center of said rotatable member, said last-named means including a shaft mounted to be rocked, and means actuated by said shaft for shifting said elements relative to each other.

9. In a wood-working machine, the com-

bination of a pattern-tracer, a cutter, means operatively connecting together said tracer and cutter, means for causing said tracer to move around, and in contact with, a pattern, and including a rotatable member and a member having engagement with said rotatable member and actuated by the latter to travel about the center of said rotatable member when said tracer engages a pattern, 5 said second-named member being shiftable toward, and away from, the center of said rotatable member, the position occupied by said second-named member relative to the center of said rotatable member being dependent on the thickness of that portion of the pattern 70 which is in engagement with the tracer, and means operating automatically to reduce the speed at which said rotatable member travels when said second-named member moves away from the center of said rotatable member and to increase the speed at which said rotatable member travels when 75 said second-named member moves toward the center of said rotatable member, said last-named means including a shiftable device connected with said second-named member at the end thereof opposite that which engages said rotatable member and at a point substantially coincident with the axis of said second-named member whereby 80 in the tilting of said second-named member to different positions, said shiftable device is caused to be shifted.

10. In a wood-working machine, the combination of a pattern-tracer, a cutter, means operatively connecting together said tracer and cutter, means for causing said tracer to move around, and in contact with, a pattern, and including a rotatable member and a tilttable member having eccentric engagement at one end with said rotatable member and actuated by the latter to travel about 15 the center of said rotatable member when said tracer engages a pattern, said second-named member being shiftable toward, and away from, the center of said rotatable member, the position occupied by said second-named member relative to the center of said rotatable member being dependent on the thickness of that portion of the pattern 20 which is in engagement with the tracer, and means operatively engaging, and actuated 25 by, said second-named member operating automatically to reduce the speed at which said rotatable member travels when said second-named member moves away from the center of said rotatable member and to increase the speed at which said rotatable member travels when said second-named member moves toward the center of said rotatable member.

11. In a wood-working machine, the combination of a pattern-tracer, a cutter, means operatively connecting together said tracer and cutter, means for causing said tracer to move around, and in contact with, a pattern, and including a rotatable member, and a 30 tilttable member having eccentric engagement at one end with said rotatable member and actuated by the latter to travel about the center of said rotatable member when said tracer engages a pattern, said second-named member being shiftable toward, and 35

away from, the center of said rotatable member, the position occupied by said second-named member relative to the center of said rotatable member being dependent on the thickness of that portion of the pattern 70 which is in engagement with the tracer, and means operating automatically to reduce the speed at which said rotatable member travels when said second-named member moves away from the center of said rotatable member and to increase the speed at which said rotatable member travels when 75 said second-named member moves toward the center of said rotatable member, said last-named means including a shiftable device connected with said second-named member at the end thereof opposite that which engages said rotatable member and at a point substantially coincident with the axis of said second-named member whereby 80 in the tilting of said second-named member to different positions, said shiftable device is caused to be shifted.

12. In a wood-working machine, the combination of a pattern-tracer, a cutter, means operatively connecting together said tracer and cutter, means for causing said tracer to move around, and in contact with, a pattern, and including a rotatable member and a tilttable member having eccentric engagement at one end with said rotatable member and actuated by the latter to travel about the center of said rotatable member when said tracer engages a pattern, said second-named member being shiftable toward, and 90 away from, the center of said rotatable member, the position occupied by said second-named member relative to the center of said rotatable member being dependent on the thickness of that portion of the pattern 95 which is in engagement with the tracer, and means operating automatically to reduce the speed at which said rotatable member travels when said second-named member moves away from the center of said rotatable member and to increase the speed at which said rotatable member travels when 100 said second-named member moves toward the center of said rotatable member, said last-named means including a shiftable device connected with said second-named member at the end thereof opposite that which engages said rotatable member and at a point substantially coincident with the axis of said second-named member whereby 105 in the tilting of said second-named member to different positions, said shiftable device is caused to be shifted.

13. In a wood-working machine, the combination of a pattern-tracer, a cutter, means operatively connecting together said tracer and cutter, means for causing said tracer to move around, and in contact with, a pattern, and including a rotatable member, and a 110

tiltable member having eccentric engagement at one end with said rotatable member and actuated by the latter to travel about the center of said rotatable member when said tracer engages a pattern, said second-named member being shiftable toward, and away from, the center of said rotatable member, the position occupied by said second-named member relative to the center of said rotatable member being dependent on the thickness of that portion of the pattern which is in engagement with the tracer, and means operating automatically to reduce the speed at which said rotatable member travels when said second-named member moves away from the center of said rotatable member and to increase the speed at which said rotatable member travels when said second-named member moves toward the center of said rotatable member, said last-named means including a shiftable device which operatively engages said second-named member and is moved into different positions by the action of said second-named member in tilting to different positions, and a rock-shaft with which said shiftable device is eccentrically connected.

14. In a wood-working machine, the combination of a pattern-tracer, a cutter, means operatively connecting together said tracer and cutter, means for causing said tracer to move around, and in contact with, a pattern, and including a rotatable member, and a tiltable member having eccentric engagement at one end with said rotatable member and actuated by the latter to travel about the center of said rotatable member when said tracer engages a pattern, said second-named member being shiftable toward, and away from, the center of said rotatable member, the position occupied by said second-named member relative to the center of said rotatable member being dependent on the thickness of that portion of the pattern which is in engagement with the tracer, and means operating automatically to reduce the speed at which said rotatable member travels when said second-named member moves away from the center of said rotatable member and to increase the speed at which said rotatable member travels when said second-named member moves toward the center of said rotatable member, said last-named means including a relatively rigid shiftable device connected with the end of said second-named member opposite that at which the latter engages said rotatable member, by a universal joint connection whereby the tilting of said second-named member to different positions actuates said shiftable device, and a rock-shaft with which said shiftable device is eccentrically connected.

15. In a wood-working machine, the combination of a pattern-tracer, a cutter, means operatively connecting together said tracer

and cutter, and means for causing said tracer to move around, and in contact with, a pattern and operating automatically to regulate the speed of movement of said tracer and cutter respectively, in the movements of these parts through paths at different distances from the axes of said pattern and work. 70

16. In a wood-working machine, the combination of a pattern-tracer, a cutter, means operatively connecting together said tracer and cutter, and means for causing said tracer to move around, and in contact with, a pattern and operating automatically to cause the tracer and cutter to travel at substantially uniform speed throughout their movement about the pattern and work respectively, in paths non-concentric with the axes of the pattern and work. 75 80

17. In a wood-working machine, the combination of a pattern-tracer, a cutter, means operatively connecting together said tracer and cutter, and means for causing said tracer to move around, and in contact with, a pattern and operating automatically to cause the tracer and cutter to be moved faster around the pattern and work respectively in the movement of the tracer and cutter into engagement with portions of the pattern and work of less cross-sectional area. 85 90

18. In a wood-working machine, the combination of a pattern-tracer, a cutter, adjustable means operatively connecting together said tracer and cutter, and means for causing said tracer to move around, and in contact with, a pattern and operating automatically to regulate the speed of movement of said tracer and cutter respectively, in the movements of these parts through paths at different distances from the axes of said pattern and work. 95 100 105

19. In a wood-working machine, the combination of a pattern-tracer, a cutter, adjustable means operatively connecting said tracer and cutter, and means for causing said tracer to move around, and in contact with, a pattern and operating automatically to cause the tracer and cutter to travel at substantially uniform speed throughout their movement about the pattern and work respectively, in paths non-concentric with the axes of the pattern and work. 110 115

20. In a wood-working machine, the combination of a pattern-tracer, a cutter, adjustable means operatively connecting together said tracer and cutter, and means for causing said tracer to move around, and in contact with, a pattern and operating automatically to cause the tracer and cutter to be moved faster around the pattern and work respectively in the movement of the tracer and cutter into engagement with portions of the pattern and work of less cross-sectional area. 120 125

21. In a wood-working machine, the com- 130

- bination of a pattern-tracer, a cutter, means operatively connecting together said tracer and cutter, a rotatable member, a member having engagement with said rotatable member and actuated by the latter to travel about the center of said rotatable member when said tracer engages a pattern, said second-named member being shiftable toward, and away from, the center of said rotatable member, means operatively connecting said second-named member and said tracer and cutter and operating to cause said second-named member to be shifted to eccentric position relative to said rotatable member when said tracer engages a pattern, a device tending to move said second-named member toward the center of said rotatable member, and an auxiliary spring device for supplementing the action of said first-named device.
22. In a wood-working machine, the combination of a pattern-tracer, a cutter, means operatively connecting together said tracer and cutter, a rotatable member, a member having engagement with said rotatable

member and actuated by the latter to travel about the center of said rotatable member when said tracer engages a pattern, said second-named member being shiftable toward, and away from, the center of said rotatable member, means operatively connecting said second-named member and said tracer and cutter and operating to cause said second-named member to be shifted to eccentric position relative to said rotatable member when said tracer engages a pattern, a device tending to move said second-named member toward the center of said rotatable member, means operating automatically to cause said rotatable member to be driven slower when said tracer moves away from the axis of the pattern and to cause said rotatable member to be driven faster when said tracer moves toward the axis of said pattern, and an auxiliary spring device connected with said means and supplementing the action of said first-named device.
